TELEPHONE SYSTEM

John H. Voss, Downers Grove, Ill., assignor to
 Associated Electric Laboratories, Inc., Chicago,
 Ill., a corporation of Delaware

Application August 3, 1940, Serial No. 350,465

15 Claims. (Cl. 179—18)

The present invention relates to telephone systems and more particularly to improvements in trunk circuit apparatus of the character utilized in terminating inter-exchange trunks in an exchange of the automatic type.

In small community automatic exchanges, commonly known as C. A. X's, the character of the automatic switching equipment is frequently such that the outlet contacts of the finder and connector switches utilized are arranged in sets for subscriber line termination, and the corresponding contacts of the contact sets having the same directory number designations are conductively connected together. This line multiple arrangement, wherein the private or control contacts as well as the talking contacts of the corresponding contact sets are conductively connected, is known as a straight multiple. While this type of outlet contact multiple is entirely adaptable to subscriber line termination, it is not well adapted for use in conjunction with the conventional trunk circuits now used to terminate inter-exchange trunks. More specifically, conventional trunk circuit arrangements require, for proper operation, a separation of the control leads extending to the finder switches from the control leads extending to the connector switches.

It is an object of the present invention, therefore, to provide in a system of the character described, an improved trunk circuit, which is so arranged that it may be directly substituted for a subscriber line circuit without in any way altering the multiple wiring of the finder and connector switches or the equipment common to these switches.

It is another object of the invention to provide an improved trunk circuit of the character noted, which is equipped to provide supervisory and trunk lockout facilities, and is extremely simple in arrangement.

It is a further object of the invention to provide in a telephone system of the character described, an improved trunk circuit arrangement wherein two trunk circuits, each adapted for use with trunks individual thereto, are cooperatively used in conjunction with a single trunk and two sets of outlet contacts of the associated finder and connector switches, so that the trunk may be seized by a connector switch as a first choice trunk for one type of call and as a second choice trunk for another type of call.

In the illustrated embodiment of the invention there is provided a small community exchange which is connected with a central exchange of the manual type by means of inter-office trunks

of two types, namely, toll and free service trunks. The community exchange is of the automatic type, finder-connector links and common equipment including a link distributor being provided 5 therein for setting up connections between the lines terminating at the exchange. Straight line multiples between the outlet contacts of the link finder and connector switches are used, so that a subscriber line connection may be made by connecting the subscriber line equipment, i. e., the line, cut-off and lockout relays directly to the private and talking leads of a particular multiple having the desired directory number designation. Each of the trunks utilized solely for toll service 10 and free service are terminated in the C. A. X in trunk circuits individual thereto, these trunk circuits being so connected and arranged that they may be directly connected to a subscriber line multiple individual thereto. Each of these 15 trunk circuits is so connected and arranged that by disconnecting a set of subscriber line relay equipment from a line multiple the talking and private leads of the trunk circuit may be directly connected to the talking and private leads of the 20 selected multiple. These trunk circuits individually comprise line, lockout and cut-off relays which are so arranged that the associated trunk is locked out of service when a permanent calling condition exists thereon. Each trunk circuit further includes a supervisory relay which is controllable over the private lead of an associated line multiple to transmit on-hook and off-hook 25 supervisory signals over the associated trunk through the expedient of reversely connecting the talking conductors of the associated trunk to the talking conductors of the associated line multiple.

One of the trunks connecting the C. A. X with the manual office is used as a combination toll and free service trunk. More specifically, this 30 trunk is normally used as a first choice, free service trunk, but provisions are made whereby it may be used as a second choice toll trunk on calls routed from the substations served by the C. A. X to the central exchange. The provisions whereby these combined service facilities 35 are obtained include a combination of two of the trunk circuits normally used for individual trunk termination. More specifically, the switchboard trunk sections of these two trunk circuits are individually connected to line multiples having different directory number designations, one of these 40 designations representing the first choice free service directory number, and the other designation representing the second choice toll trunk 45 designation. Both of the two trunk circuits are 50 55

equipped with line, cut-off, lockout and supervisory relays, whereby the facilities mentioned above are provided regardless of which trunk circuit is taken for use in seizing the single-associated trunk. In addition, provisions are made in the circuit arrangement formed by the combination of the two trunk circuits, whereby when either trunk circuit is seized the other trunk circuit is marked against seizure. Provisions are also made for selectively switching the associated inter-office trunk between the two trunk circuits, depending upon the type of call being handled.

The novel features believed to be characteristic of the invention are set forth with particularity in the appended claims. The invention, both as to its organization and method of operation, together with further objects and advantages thereof, will best be understood by reference to the specification taken in connection with the accompanying drawings, in which Figures 1 and 2, considered together, illustrate a telephone system having incorporated therein the features of the invention as briefly outlined above.

Referring now more particularly to the drawings, the system there illustrated comprises a manual office 5 and a C. A. X 10, each of which is arranged for subscriber line termination. These two exchanges are inter-connected by means of a group of toll trunks including the trunk 01 and a group of free service trunks. An additional trunk 91 is provided which, in the arrangement illustrated, is utilized as a first choice free service trunk and as a second class toll trunk. These trunks terminate in the central exchange 5 at different operators' positions of an operator's switchboard 6 which may be entirely conventional in arrangement.

The automatic switching apparatus provided in the C. A. X 10 is preferably of the character disclosed and claimed in applicant's copending application, Serial No. 189,121, filed February 7, 1938. Briefly described, this apparatus comprises a plurality of finder-connector links, one of which is indicated at 15 as including the finder switch 25 and the connector switch 30, and common equipment 20. The finder and connector switches are of the all-relay type, group and unit relays arranged in a novel manner being provided in each switch for performing the required line-selecting functions. Each of the finder switches is fully selective in character, auxiliary group and unit relays being provided in the common equipment 20 for causing the instantaneous operation of the corresponding relays in an assigned finder switch in response to the initiation of a call on one of the lines accessible to the links. The links are successively assigned for use in a predetermined order through the provision of a link distributor which is also of the all-relay type. Straight line multiples are utilized to connect the corresponding contacts of the link finder and connector switches. Thus, the outlet contacts forming the contact set 11f of the finder switch 25 are conductively connected by means of two talking leads and a private lead directly to the outlet contacts forming the contact set 11c of the connector switch 30. This multiple is also extended to the contact sets having the directory number designation X11X of the other link finder and connector switches. In a similar manner, the finder outlet contacts 01f are directly multiplied to the connector outlet contacts 01c; the finder outlet contacts 02f are directly multiplied to the connector outlet contacts 02c; and the 75

finder outlet contacts 91f are directly multiplied to the connector outlet contacts 91c. These line multiples are carried to a distributing frame at which connections are made to the subscriber line equipment. Thus, the line circuit 12, which is provided in association with the subscriber line 11 serving the substation A, may be connected to the line multiple having any desired directory number designation by making three connections at the distributing frame. In the arrangement illustrated, this line circuit is connected to the line multiple having the directory number designation X11X.

Each of the inner-office trunks inter-connecting the C. A. X 10 and the central exchange 5 is terminated in a trunk circuit which is connected and arranged in accordance with the present invention. Thus, the toll trunk 01 extends to a trunk circuit 35 having a trunk section which is connected to the outlet contact multiple having the directory number designation 01. The arrangement of the trunk circuit 35 is identical with the arrangement of the trunk circuit 40, which may either be used to terminate a second toll trunk 02 illustrated in dotted lines, or may be used in conjunction with the trunk circuit 45 to terminate the combination toll and free service trunk 91. Each of the trunk circuits which terminates a toll or free service trunk individual thereto is identical in arrangement with the trunk circuit 40. Briefly described, this trunk circuit comprises a line relay R110, a cut-off relay R120, a slow-acting lockout relay R100, a supervisory relay R130 and circuit connections therebetween which are described more fully in the following portion of the specification dealing with the operation of the system. The trunk circuit 45 is substantially similar in arrangement with the trunk circuit 40. More specifically, the trunk circuit 45 comprises a line relay R210, a cut-off relay R220, a lockout relay R200 of the slow-acting type, a supervisory relay R230, a line-switching relay R240 and a guard control relay R250. The two last-mentioned relays are provided for the purpose of correlating the operation of the two trunk circuits. In this regard it will be noted that the trunk 91 may be seized through the trunk circuit 45 directly over the trunk section 156 having the directory number designation 91, or may be seized through the trunk circuit 40 over the trunk section 149 having the directory number designation 02. If more than one toll trunk is required between the central exchange 5 and the C. A. X 10, the switchboard side of the trunk circuit 40 is connected to the outlet contact multiple having the largest directory number. Thus, if three such trunks, in addition to a combination trunk, are required, the associated trunk circuits are connected to the line multiples having the directory number designations 01, 02 and 03, and the trunk circuit 40 is connected to the line multiple having the directory number designation 04. In any case where more than one toll trunk is provided, it is necessary to make provisions for automatic trunk selection. To this end there is associated with the finder-connector links of the C. A. X 10 a set of trunk preselect relays 50 which are of the character disclosed in Figs. 11 and 13 of the above-mentioned copending application Serial No. 189,121 now U. S. Patent 2,252,309, granted August 12, 1941. Briefly described, these relays are so arranged that when the first trunk of a group, such, for example, as the trunk 01, becomes busy, it is marked as busy in all of the finder and

connector switches, and the second trunk, namely, the trunk 02, is immediately allotted for use. If the second trunk is also busy at the time the first trunk is taken for use, the third trunk, if idle, is allotted for use. Further, the arrangement of this relay group is such that the trunk having the lowest directory number designation is assigned for use in preference to the other trunks, so long as it is not occupied with a call.

The operation of the trunk circuits 35, 40, etc., individually terminating the toll and free service trunks, in handling calls incoming to the C. A. X 10, may best be understood by considering the trunk circuit 40 as being used to terminate the toll trunk 02. In such case, the conductors C215, C216, C217 and C218 are disconnected from the terminals 108, 109, 117 and 118, respectively, the talking conductors of the toll trunk 02 are connected to the terminals 108 and 109, and the terminals 117 and 118 are strapped or otherwise conductively connected. With this wiring arrangement, if one of the operators attending the switchboard 6 inserts the calling plug of one of her cord circuits in the jack terminating the toll trunk 02, a direct current path is bridged across the talking conductors of this trunk to complete a circuit including the conductors C115 and C116, and the contacts 121 and 125 for energizing the line relay R100. In operating, the relay R100 closes its contacts 111 to prepare a locking circuit for the lockout relay R100, and moves its contacts 112 out of engagement to open a point in the operating circuit for the supervisory relay R130. At its contacts 113, the relay R110 completes an obvious path for impressing ground potential upon the group select lead C106. At its contacts 114, the relay R110 connects the unit select lead C107 through the contacts 105 to the start lead C208. When the group select lead C106 is grounded, and the leads C107 and C208 are connected together, the auxiliary relays of the common equipment 20 operate to cause the operation of the corresponding relays in the finder switch of the assigned link. Assuming that the link 15 is assigned to handle the call, the tenth group relay and the second unit relay of the finder switch 25 operate to extend a connection from the trunk section 150 to the connector portion of the link. Incident to the operation of the relay equipment embodied in the finder switch 25, a circuit is completed for energizing the line relay of the connector switch 30, whereby the line, hold and impulse-correcting relays of this connector switch are caused to operate. These relays, in operating, function momentarily to impress ground potential upon the conductor C159 and to impress ground potential upon the control conductor C152 for the duration of the call. When the control conductor C152 is grounded, the trunk preselect relays 50 operate to mark the trunk 02 against seizure in all of the link connector switches. When the positive talking conductor C159 is grounded, a circuit including the contacts 122 and 124 is completed for energizing the upper winding of the cut-off relay R120. The relay R120 now operates and locks to ground over a path including the contacts 123 and 125, the strapped terminals 117 and 118, and the grounded conductor C152. After this locking circuit is completed, the relay R120 opens its operating circuit at the contacts 124. At its contacts 126, the relay R120 completes an obvious circuit for energizing the slow-acting lockout relay R100. At its contacts 127, the relay R120 opens another point in the oper-

ating circuit for the supervisory relay R130. At its contacts 121 and 125, the relay R120 opens two points in the above-traced operating circuit for the line relay R110 and, in so doing, clears

5 the trunk 02 of the impedance represented by the windings of the line relay. At its contacts 122, the relay R120 extends the calling loop through the contacts 132 and 137, and the contacts of the operated relays in the finder switch 25 to 10 the connector portion of the link 15, thus establishing a pulsing circuit for the line relay of the connector switch 30.

The line relay R110, upon restoring, closes its contacts 112 to reprepare the operating circuit 15 for the supervisory relay R130, and opens its contacts 113 to disconnect the group select lead C106 from ground. At its contacts 111, the relay R110 opens a point in the locking circuit for the lockout relay R100. At its contacts 114, the relay 20 R110 disconnects the units select lead C107 from the start lead C208. The lockout relay R100, upon operating, prepares its locking circuit at the contacts 101, and closes its contacts 102 to prepare another path for impressing ground potential 25 upon the control conductor C152. At its contacts 103, the relay R100 opens another point in the operating circuit for the supervisory relay R130. At its contacts 104, the relay R100 opens another point in the path for grounding the 30 group select lead C106. At its contacts 105, the relay R100 opens a further point in the path for connecting the units select lead C107 to the start lead C208.

When the units select lead C107 is disconnected 35 from the start lead C208, and the group select lead C106 is disconnected from ground, the operated auxiliary relays embodied in the common equipment 20 are deenergized and restore. Incident to the operation of the relay equipment embodied in the link 15, the link distributor relays forming a part of the common equipment 20 are caused to operate to select another idle link, and the link 15 is marked against seizure. Thus, the common equipment 20 is freed for use 45 in handling another call which may be waiting or which may be subsequently initiated.

Following the extension of the connection to the connector portion of the link 15 in the manner explained above, the operator handling the 50 call at the operator's switchboard 6 in the central exchange 5, may extend the connection to the desired line, and cause ringing current of the frequency or code designating the desired substation to be projected over this line by dialing a 55 four digit directory number. The first digit is utilized to determine the type of ringing to be employed in signaling over the called line, i. e., bridged or divided ringing and partially to select the ringing code or frequency of the ringing current. The second digit is utilized for the purpose of causing the operation of the connector group relay which terminates the group of ten lines including the called line. Thus, if the substation A, served by the line 11, is called, the dialing of the second digit will result in the operation of the first group relay of the connector switch 30. The third digit dialed at the calling operator's 65 position 6 in the manual exchange 5 is utilized for the purpose of causing the operation of the connector unit relays which correspond to the particular desired line. In the case under consideration, the first unit relay of the connector switch 30 will be operated in response to the dialing of the third digit. The fourth digit dialed 70 is used to complete the selection of the particular

code or frequency of the ringing current to be projected over the selected line 11. Immediately after the called line 11 is selected it is tested to determine the idle or busy condition thereof. In the event the line is busy, the usual busy tone signal is transmitted over the trunk 02 to inform the calling operator that the desired connection cannot be obtained, and the ringing circuits are held open to prevent the transmission of ringing current over the selected line. On the other hand, if the called line is idle, ringing current of the selected code or frequency is projected thereover for the purpose of energizing the signal device provided at the called substation. Assuming that the line 11 is of the multi-party type and that coded ringing is used, the ringing current transmitted over this line may also result in the operation of the ringers provided at certain of the other substations served by this line but the coded character of the signals produced indicates that only the substation A is being called. The desired conversational circuit is established when the call is answered at the called substation A. In response to this operation, the back-bridge relay embodied in the connector switch 30 operates to reverse the direction of current flow over the conductors of the trunk 02 in the usual manner. This current reversal causes the operation of a polarized supervisory relay embodied in the trunk circuit terminating the toll trunk 02 at the operator's switchboard 6, whereby an off-hook supervisory signal is produced at the calling operator's position of this switchboard, indicating that the call has been answered. The back-bridge relay of the connector switch 30 also follows the connection release and the call answering operations which may subsequently be performed by manipulation of the switchhook provided at the substation A, so that the usual flashing recall and disconnect signals are produced by the supervisory lamp associated with the connection at the calling operator's position in the central exchange 5. Thus, the operator handling the call may be informed that she is being recalled by the called party and is also informed when the connection is released at the called substation.

The release of the connection is entirely under the control of the operator handling the call at the switchboard 6 in the central exchange 5. More specifically, when a disconnect or on-hook supervisory signal is transmitted to the calling operator, indicating that the connection has been released at the called substation, the operator may initiate the release of the switch train by withdrawing the calling plug of the cord circuit included in the connection from the jack terminating the trunk 02. In response to this operation, the loop circuit extending from the calling operator's position to the connector switch 30 is interrupted to cause the deenergization and release of the line and hold relays embodied in this switch. When the hold relay of the connector switch 30 restores, the finder and connector switches 25 and 30, respectively, and the line circuit 12 are restored to normal in the manner explained in detail in the above-mentioned copending application. During the release of the link 15, the link is marked as idle in the distributor relays of the common equipment 20, and ground potential is removed from the control conductor C152 of the trunk section 149. When this control conductor is disconnected from ground, the cut-off relay R120 is deenergized and restores to open, at its contacts 126, the operating circuit for the

lockout relay R100. Following the release of the lockout relay R100, the trunk circuit 40 is fully restored to normal and is marked as idle in the trunk preselect relay group 50.

As indicated in the introductory portion of the specification, provisions are made in the trunk circuit 40 for locking this circuit and the associated trunk 02, if used, out of service when a permanent calling condition occasioned by a fault or the like is present on this trunk. Under these circumstances, the link 15, for example, may be seized in the manner explained above, but, following seizure thereof, no dial pulses are transmitted to the connector switch 30. When the link 15 is seized, a timing device common to the links of the exchange is conditioned forcibly to release the link after the expiration of a predetermined time interval in the event a talking circuit is not established by way of the link before the predetermined time interval expires. Should this contingency be met, the control equipment of the link 15, in releasing, disconnects the control conductor C152 from ground, whereby the operated cut-off relay R120 is deenergized and restores. This relay, in releasing, reconnects the windings of the line relay R110 to the conductors of the trunk 02 upon which the calling condition is still present. Accordingly, the line relay R110 reoperates to complete, at its contacts 111, the prepared locking circuit for the still operated lockout relay R100. Thus, the line and lockout relays R110 and R100, respectively, are locked energized. With the relay R100 operated, and the cut-off relay R120 in its restored position, an auxiliary path including the contacts 102 and 127 is completed for maintaining ground potential upon the control conductor C152, whereby the trunk circuit 40 is guarded against seizure by one of the connector switches provided in the C. A. X. With the lockout relay R100 operated, the start circuits described above, and including the group select lead C106, the units select lead C107 and the start lead C108, are held open to prevent the finder portion of an assigned link from operating to seize the trunk section 149. It will be obvious that the two relays R110 and R100 remain in their respective operated positions until the permanent calling condition present on the toll trunk 02 is cleared. When the fault responsible for this condition is corrected, the line relay R110 is deenergized and restores to cause the release of the lockout relay R100 in an obvious manner. With these two relays restored, the trunk circuit 40 is fully released, and this circuit is marked as idle in the relays of the trunk preselect group 50.

The manner in which the trunk circuit 45 operates in the extension of a call from the operator's switchboard 6 by way of the trunk 91 and the link 15, for example, to the subscriber line 11, for example, is substantially similar to the mode of operation of the trunk circuit 40 as described above. In this regard it will be understood from the preceding explanation that the trunk circuit 45 is in all cases used in conjunction with the trunk circuit 40 or the equivalent thereof, and terminates a combination toll and free service trunk. More specifically, if one of the operators having access to the trunk 91 at the operator's switchboard 6 inserts the calling plug of one of her cord circuits in the jack terminating the conductors of this trunk to establish a direct current path between the talking conductors of the trunk, the line relay R210 is energized

and operates. Upon operating, the relay R210 closes its contacts 213 to impress ground potential upon the group select lead C206, and closes its contacts 214 to connect the units select lead C207 to the start lead C208. In response to these operations, the finder portion of the assigned link, such, for example, as the link 15, is caused to operate to seize the trunk circuit 45 over the trunk section 156 in the manner described above. The line relay R210, in operating, also opens, at its contacts 212, a point in the operating circuit for the supervisory relay R230. At its contacts 211, the relay R210 completes an obvious circuit for energizing the guard control relay R250. The relay R250, upon operating, closes its contacts 252 to complete an obvious path for impressing ground potential upon the connected control conductors C218 and C152, whereby the trunk circuit 40 is marked against seizure over the trunk section 149 by one of the connector switches provided in the C. A. X 10. At its contacts 251, the relay R250 opens a point in the operating circuit for the switching relay R240.

When the finder switch 25 of the assigned link 15 operates to extend the connection from the trunk section 156 to the connector switch 30, the control relays of the connector switch operate momentarily to impress ground potential upon the positive talking conductor C153, thereby to cause the energization of the cut-off relay R220 over a circuit including this talking conductor and the contacts 222 and 224. Coincident with the energization of the relay R220, ground potential is impressed upon the control conductor C154 by the control relays of the connector switch 30, whereby the trunk circuit 45 is marked against seizure by another of the connector switches. The cut-off relay R220, upon operating, locks to the grounded control conductor C155 over a path including the contacts 223, 236 and 246. After this locking circuit is completed, the relay R220 opens its contacts 224 to interrupt its operating circuit. At its contacts 221 and 225, the relay R220 disconnects the windings of the line relay R210 from the conductors of the trunk 91. At its contacts 222, the relay R220 extends the calling loop circuit to the connector portion of the link. At its contacts 226, the relay R220 completes an obvious operating circuit for the slow-acting lockout relay R200. At its contacts 227, the relay R220 opens a point in the operating circuit for the supervisory relay R230. The line relay R210, upon restoring in response to operation of the cut-off relay R220, opens its contacts 213 and 214 included in the start circuits extending to the common equipment 20, whereby the operated relays of this equipment are deenergized and restore to condition the common equipment for use in handling another call. At its contacts 212, the relay R210 prepares the operating circuit for the relay R230. The lockout relay R200, upon operating, opens its contacts 204 and 205 further to interrupt the start circuits extending to the common equipment 20. At its contacts 203, the relay R200 opens another point in the operating circuit for the supervisory relay R230. At its contacts 202, the relay R200 prepares an alternative path for impressing ground potential upon the control conductor C155. At its contacts 201, the relay R200 prepares a locking circuit for itself, and completes a locking circuit for the guard control relay R250, the latter circuit extending from ground by way of the contacts 226 and 201, and the winding of R250 to battery.

After the connection has been extended through the trunk circuit 45 to the connector switch 30, it may be forwarded to the substation A, for example, served by the line 11, in the exact manner described above with reference to the call routed through the trunk circuit 40. Supervision of the call is under the control of the back-bridge relay embodied in the connector switch 30, this relay being arranged to follow the connection release and call answering operations performed at the called substation A to transmit corresponding supervisory signals to the position of the operator handling the call at the operator's switchboard 6 in the central exchange 5. The release of the connection is also accomplished in a manner similar to that described above with reference to the trunk circuit 40. Thus, when the operator receives a disconnect signal and withdraws the calling plug of the cord circuit included in the connection from the plug terminating the conductors of the trunk 91, the operated relays of the link 15 are caused to release, the line circuit 12 is released, and the link 15 is marked as idle in the distributor relays of the common equipment 20. During the release of the link 15, ground potential is removed from the control conductor C155 to cause the deenergization and release of the cut-off relay R220. This relay, upon restoring, opens the operating circuit for the lockout relay R200, and the locking circuit for the guard control relay R250. When the two last-mentioned relays restore, the trunk circuit 45 is fully released, and both this circuit and the trunk circuit 40 are marked as idle.

The manner in which the four relays R220, R210, R200 and R250 cooperate to lock the trunk 91 and the two trunk circuits 40 and 45 out of service when a permanent calling condition is present on the trunk 91 is substantially similar to the mode of operation of the relays R120, R110 and R100 to accomplish this end, and will be clearly apparent from the foregoing explanation of the operation of the three latter relays to lock to the trunk 02 and the trunk circuit 40 out of service when a permanent calling condition exists on the trunk 02.

As indicated above, the toll trunks 01 and 02 may be used for routing toll calls from the sub-stations served by the C. A. X 10 to the toll operator's position provided at the switchboard 6 in the central exchange 5. If desired, provisions may be made whereby these toll trunks are used in handling C. A. X subscriber calls to the central exchange subscribers when the calls are initiated at substations serving subscribers who pay only for local exchange service and are to be charged for central office calls. In such case, the other C. A. X subscribers, namely, those paying a higher rate for both local and central exchange service, are permitted to have access to the free service trunks and to the combination toll and free service trunk 91.

Assuming that a call initiated at the substation A is to be routed to the toll operator's position at the switchboard 6 and, further, that the link 15 is assigned to the use of the call, the calling subscriber, after initiating the call in the usual manner to cause the seizure of the line 11 by the finder switch 25, dials the four digits necessary to cause the connector switch 30 to seize the trunk section 149 terminating at the contact set having the 02 directory number designation. It will be understood that if the first trunk 01 is idle, the trunk circuit 35 is seized, and the trunk 01 is utilized in forwarding the

call to the toll operator's position at the switchboard 6. On the other hand, if the toll trunk 01 is busy and the toll trunk 02 is idle at the time the call is initiated, the trunk preselect relays 50 occupy a position such that the connector switch 30 automatically seizes the trunk circuit 40. Incident to the seizure of this trunk circuit, the control equipment of the connector switch 30 functions to complete a loop circuit between the connector switch 30 and the trunk circuit 40, and to impress ground potential upon the control conductor C152. When the conductor C152 is connected to ground, the relay R130 is energized over a circuit including this conductor, the strapped terminals 118 and 117, and the contacts 127, 103 and 112. Upon operating, the relay R130 locks to the grounded control conductor C152 over a path including its contacts 136, and opens, at its contacts 135, a point in the above-traced locking circuit for the cut-off relay R120. At its contacts 133, the relay R130 completes an obvious circuit for energizing the lower winding of the cut-off relay R120. The relay R120, upon operating, completes the operating circuit for the lockout relay R100, disconnects the windings of the line relay R110 from the conductors of the trunk 02, and connects the trunk conductor C115 to the talking conductor C151 of the trunk section 149. In this regard it will be apparent that when the relay R130 operates, it prepares, at its contacts 131, 132, 134 and 137, paths for reversely connecting the conductors C115 and C116 to the conductors C150 and C151, whereby an off-hook supervisory signal is produced at the toll operator's position of the switchboard 6 when the call is answered.

The lockout relay R100, upon operating, opens its contacts 103 to interrupt the above-traced operating circuit for the relay R130. At its contacts 104 and 105, the relay R100 further opens the start circuits extending to the common equipment 20. At its contacts 101, the relay R100 prepares its locking circuit, and, at its contacts 102, prepares one of the previously traced paths for impressing ground potential upon the control conductor C152. Following the operation of the relay R100, no further operation of the relay equipment embodied in the trunk circuit 40 occurs until the connection is released at the calling substation A. After the relay R120 operates reversely to connect the talking conductors of the trunk 02 to the talking conductors of the trunk section 149, the ringing control equipment of the connector switch 30 functions to transmit ringing current over the trunk section 149, through the trunk circuit 40 and over the trunk 02 for the purpose of energizing the drop or other ringing current controlled signal device provided at the toll operator's position of the switchboard 6 in association with this trunk. The operation of this signal device serves to inform the operator attending the toll position that a call is present on the trunk 02 which should be answered. After the call is answered, the toll operator may converse with the calling subscriber at the substation A to ascertain the identity of the desired substation or party, and may forward the connection to the desired substation in a manner well understood in the art.

The release of the connection extending between the substation A and the toll operator's position at the switchboard 6, is entirely under the control of the calling subscriber. Thus, when the connection is released at the substation A, the line circuit 12 and the link 15 are caused

to release in the manner briefly described above and pointed out with particularity in the previously referred to copending application. During the release of the link 15, ground potential is removed from the control conductor C152 to cause the deenergization of the relay R130. This relay, upon restoring its contacts 131, 132, 134 and 137 to normal, reverses the direction of current flow over the conductors of the trunk 02, whereby the usual disconnect signal is produced by the supervisory signal lamp associated with this trunk at the toll operator's position of the switchboard 6. In releasing, the relay R130 also opens the operating circuit for the relay R120. The relay R120 now restores to bridge the windings of the line relay R110 across the conductors of the trunk 02. In the event the connection has not been cleared out at the toll operator's position of the switchboard 6 prior to the release of the connection at the substation A, the conductors of the trunk 02 are connected together over a direct current path extending through the operator's cord circuit in use at the toll operator's position. Accordingly, the line relay R110 is energized when its windings are bridged across the conductors of the trunk 02, and operates to complete the locking circuit for the lockout relay R100. The two relays R110 and R100 are thus held operated until the connection is cleared out at the toll operator's position of the switchboard 6. With these two relays operated and the two relays R120 and R130 restored, the previously traced path including the contacts 102 and 127 is completed for impressing ground potential upon the control conductor C152, thereby to guard the trunk circuit 40 against seizure. It will be apparent that when the connection is cleared out at the toll operator's position of the switchboard 6, the relays R110 and R100 are sequentially de-energized and restore, whereby the trunk circuit 40 is fully released and is identified as idle in the trunk preselect relay group 50. If, on the other hand, the connection is cleared out at the toll operator's position of the switchboard 6 prior to its release at the calling substation A, the line relay R110 is not energized in response to the release of the cut-off relay R120. Accordingly, the three relays R130, R120 and R100 sequentially restore in the order named and in a manner clearly apparent from the above explanation when the control equipment of the link 15 functions to disconnect the control conductor C152 from ground.

Assuming that the trunk circuit 40 is used in conjunction with the trunk circuit 45 to terminate the combination toll and free service trunk 91, the relay operations which occur incident to the extension of the above-described call to the trunk circuit 40, are substantially the same as described above. With the latter arrangement, however, the switching relay R240 is energized in parallel with the supervisory relay R130 when the control equipment of the connector switch 30 operates to impress ground potential upon the control conductor C152. The circuit for energizing these two relays in parallel extends by way of the grounded conductor C152 and the contacts 251 to the conductor C217 where it divides, one branch extending through the winding of R240 to battery, and the other branch extending by way of the contacts 127, 103 and 112, and the winding of R130 to battery. The relay R240, upon operating, opens its contacts 242 and 244 to disconnect the conductors of the trunk 91 from the trunk circuit 45, and closes its contacts 241 and

243 to connect these conductors to the conductors C215 and C216 which extend to the trunk circuit 40. Accordingly, the ringing current which is transmitted by the connector switch 30 over the trunk section 149 following seizure of the trunk circuit 40, is projected over the trunk 91 to energize the incoming call signal device provided in association with this trunk at the operator's switchboard 6 in the central exchange 5.

At its contacts 245, the relay R240 opens a point in the operating circuit for the relay R230. At its contacts 245, the relay R240 completes an obvious path for impressing ground potential upon the control conductor C155, thereby to guard the trunk circuit 45 against seizure by the connector switches of the C. A. X 10. In handling a call of this character, the other relays of the trunk circuit 40, namely, the relays R180, R110 and R120 operate in the exact manner described above with reference to the call routed to the toll operator's position of the switchboard 6 over the trunk 02. It will be observed that the switching relay R249 is held energized over a circuit including the connected control conductors C217, C218 and C152 until the connection is cleared out at both the calling substation A and the position of the operator handling the call at the switchboard 6 in the central exchange 5.

Since the trunk 91 is primarily provided for free service calls to the central exchange subscribers, it will normally be seized by the connector switches of the C. A. X 10 through the trunk circuit 45. Assuming, for example, that the above-described call originating at the substation A is routed through the finder-connector link 15 to the trunk circuit 45 at a time when the trunk 91 is idle, the connector switch 30, upon operating to its ringing position, impresses ground potential upon the control conductor C155 of the trunk section 156 to energize the supervisory relay R230 over a circuit including this control conductor and the contacts 246, 227, 203 and 212. Upon operating, the relay R230 completes an obvious circuit for energizing the lower winding of the cut-off relay R220, and locks to the grounded control conductor C155 over a path including its contacts 237 and the contacts 246. At the contacts 222, 231, 232, 234 and 235, the two relays R220 and R230, in operating, reversely connect the conductors of the trunk 91 to the talking conductors C153 and C154 of the trunk section 156, whereby the proper off-hook supervisory signal is produced by the signal lamp associated with the trunk 91 after the call is answered at the operator's position of the switchboard 6 at which the trunk 91 is terminated. In operating, the relay R220 also opens its contacts 221 and 225 to disconnect the windings of the line relay R210 from the conductors of the trunk 91. At its contacts 227, the relay R220 opens a point in the above-traced operating circuit for the supervisory relay R230. At its contacts 228, the relay R220 completes an obvious circuit for energizing the lockout relay R200. The relay R200, upon operating, closes its contacts 201 to prepare the previously described locking circuit for itself, and to complete the previously traced operating circuit for the guard control relay R250. At its contacts 202, the relay R200 prepares an alternative path for impressing ground potential upon the control conductor C155. At its contacts 203, the relay R200 opens another point in the operating circuit for the supervisory relay R230. At its contacts 204 and 205, the relay R200 opens further points in the start circuits individual to

the trunk circuit 45 and extending to the common equipment 20. The guard control relay R250, upon operating, closes its contacts 252 to impress ground potential upon the control conductor C152 and thus guard the trunk circuit 40 against seizure for the duration of the call. At its contacts 251, the relay R250 opens a point in the previously traced circuit for energizing the relays R240 and R130 in parallel.

After the call, as routed through the trunk circuit 45 and over the trunk 41 to the operator's switchboard 6, is answered at the position of the operator where this trunk is terminated, the answering operator may converse with the calling subscriber and ascertain the identity of the party desired or the directory number of the substation desired, and may extend the connection to the desired substation in a manner well understood in the art.

The release of the finder-connector link 15 is in this case also entirely under the control of the calling subscriber at the substation A. During the release of this link, which occurs when the calling subscriber restores the receiver provided at the substation A to its supporting hook or cradle, the control conductor C155 is disconnected from ground in the connector switch 30, thereby to deenergize the supervisory relay R230. Upon restoring, the relay R230, at its contacts 231, 232, 234 and 235 reverses the direction of current flow over the trunk 91, whereby a disconnect signal is produced at the position of the operator handling the call in the central exchange 5. Upon restoring, the relay R230 also opens its contacts 233 to deenergize the cut-off relay R220. In the event the connection has not previously been cleared out at the position of the operator handling the call in the central exchange 5, the cut-off relay R220, upon restoring, completes the operating circuit for the line relay R210. The relay R210, upon operating, closes its contacts 211 to complete the locking circuits for the guard control relay R250 and the lockout relay R200. Thus, the three relays R210, R230 and R250 are held operated until the connection is cleared out at the position of the operator handling the call in the central exchange 5. With the lockout relay R200 operated, and the cut-off relay R220 in its restored position, the control conductor C155 is connected to ground over a path including the contacts 246, 227 and 202. Thus, the trunk circuit 45 is guarded against seizure by the connector switches of the C. A. X 10. With the guard control relay R250 operated, ground potential is also impressed upon the control conductor C152 over a path including the contacts 252 to guard the trunk circuit 40 against seizure. When the connection is cleared out at the position of the operator handling the call in the central exchange 5, the line relay R210 is deenergized and restores in the manner previously explained. This relay, upon restoring, causes the sequential release of the relays R250 and R200 in an obvious manner. Thus, the trunk circuit 45 is fully restored to normal, and the two trunk circuits 40 and 45 are marked as idle. In the event the connection is cleared out at the position of the operator handling the call in the central exchange 5 prior to the release of the connection at the calling substation A, the relays R230, R220, R250 and R200 are caused sequentially to restore in the order named and in a manner clearly apparent from the above explanation. When these relays restore, the trunk circuit 45 is fully released and

both this circuit and the trunk circuit 40 are marked as idle.

While there has been described what is at present considered to be the preferred embodiment of the invention, it will be understood that various modifications may be made therein, and it is contemplated to cover in the appended claims all such modifications as fall within the true spirit and scope of the invention.

I claim:

1. In a telephone system, an exchange including automatic finder and connector switches for setting up connections between the lines of the system, the corresponding outlet contacts of said finder and connector switches being conductively connected and being arranged in sets for subscriber line termination, a pair of trunk circuits respectively including trunk sections terminated at sets of said outlet contacts having different directory number designations, a second exchange, a trunk extending from said second exchange to said trunk circuits, and means controllable through said connector switches for selectively connecting said trunk to one or the other of said trunk circuits.

2. In a telephone system, an exchange including automatic finder and connector switches for setting up connections between the lines of the system, the corresponding outlet contacts of said finder and connector switches being conductively connected and being arranged in sets for subscriber line termination, a pair of trunk circuits respectively including trunk sections terminated at sets of said outlet contacts having different directory number designations, a second exchange, a trunk extending from said second exchange to said trunk circuits, and means comprising a relay controlled over a circuit including one of the contacts of one of said pair of contact sets for selectively connecting said trunk to one or the other of said trunk circuits.

3. In a telephone system, an exchange including automatic finder and connector switches for setting up connections between the lines of the system, the corresponding outlet contacts of said finder and connector switches being conductively connected and being arranged in sets for subscriber line termination, a pair of trunk circuits respectively including trunk sections terminated at sets of said outlet contacts having different directory number designations, a second exchange, a trunk normally connected to one of said trunk circuits and extending to said second exchange, and switching means operative to disconnect said trunk from said one trunk circuit and to connect said trunk to the other of said trunk circuits.

4. In a telephone system, an exchange including automatic finder and connector switches for setting up connections between the lines of the system, the corresponding outlet contacts of said finder and connector switches being conductively connected and being arranged in sets for subscriber line termination, a pair of trunk circuits respectively including trunk sections terminated at sets of said outlet contacts having different directory number designations, a second exchange, a trunk normally connected to one of said trunk circuits and extending to said second exchange, and means comprising a relay controlled over a circuit including one of the contacts of the contact set terminating the trunk section of the other of said trunk circuits for disconnecting said trunk from said one trunk circuit.

circuit and for connecting said trunk to the other of said trunk circuits.

5. In a telephone system, an exchange including automatic finder and connector switches for setting up connections between the lines of the system, the corresponding outlet contacts of said finder and connector switches being conductively connected and said contacts being arranged in sets each including a pair of talking contacts and a control contact, a pair of trunk circuits respectively including trunk sections terminated at sets of said outlet contacts having different directory number designations, each of said trunk sections including a pair of talking conductors and a control conductor, a second exchange, a trunk extending from said second exchange to said trunk circuits, means controlled over the control conductor of one of said trunk sections for selectively connecting said trunk to said trunk circuits, and means controlled over the control conductors of said trunk sections for marking both of said trunk circuits busy when either trunk circuit is occupied with a call.

6. In a telephone system, an exchange including automatic finder and connector switches for setting up connections between the lines of the system, the corresponding outlet contacts of said finder and connector switches being conductively connected and said contacts being arranged in sets each including a pair of talking contacts and a control contact, a pair of trunk circuits respectively including trunk sections terminated at sets of said outlet contacts having different directory number designations, each of said trunk sections including a pair of talking conductors and a control conductor, a second exchange, a trunk extending from said second exchange to said trunk circuits, means controlled over the control conductor of one of said trunk sections for selectively connecting said trunk to said trunk circuits, and means responsive to the seizure of either of said trunk circuits by one of said connector switches for reversely connecting the talking conductors of said trunk to the talking conductors of the trunk section individual to the seized trunk circuit.

7. In a telephone system, an exchange including automatic finder and connector switches for setting up connections between the lines of the system, the corresponding outlet contacts of said finder and connector switches being conductively connected and said contacts being arranged in sets each including a pair of talking contacts and a control contact, a pair of trunk circuits respectively including trunk sections terminated at sets of said outlet contacts having different directory number designations, each of said trunk sections including a pair of talking conductors and a control conductor, a second exchange, a trunk extending from said second exchange to said trunk circuits, means controlled over the control conductor of one of said trunk sections for selectively connecting said trunk to said trunk circuits, and means individual to said trunk circuits and controlled over the control conductors of the associated trunk sections for reversely connecting the talking conductors of said trunk to the talking conductors of the respective associated trunk sections.

8. In a telephone system, an exchange including automatic finder and connector switches for setting up connections between the lines of the system, the corresponding outlet contacts of said finder and connector switches being conductively connected and said contacts being arranged in

sets each including a pair of talking contacts and a control contact, a pair of trunk circuits respectively including trunk sections terminated at sets of said outlet contacts having different directory number designations, each of said trunk sections including a pair of talking conductors and a control conductor, a second exchange, a trunk extending from said second exchange to said trunk circuits, means controlled over the control conductor of one of said trunk sections for selectively connecting said trunk to said trunk circuits, means controlled over the control conductors of said trunk sections for marking both of said trunk circuits busy when either trunk circuit is occupied with a call, and means responsive to the seizure of either of said trunk circuits by one of said connector switches for reversely connecting the talking conductors of said trunk to the talking conductors of the trunk section individual to the seized trunk circuit.

9. In a telephone system, an exchange including automatic finder and connector switches for setting up connections between the lines of the system, the corresponding outlet contacts of said finder and connector switches being conductively connected and said contacts being arranged in sets each including a pair of talking contacts and a control contact, a pair of trunk circuits respectively including trunk sections terminated at sets of said outlet contacts having different directory number designations, each of said trunk sections including a pair of talking conductors and a control conductor, a second exchange, a trunk extending from said second exchange to said trunk circuits, means controlled over the control conductor of one of said trunk sections for selectively connecting said trunk to said trunk circuits, means controlled over the control conductors of said trunk sections for marking both of said trunk circuits busy when either trunk circuit is occupied with a call, and means individual to said trunk circuits and controlled over the control conductors of the associated trunk sections for reversely connecting the talking conductors of said trunk to the talking conductors of the respective associated trunk sections.

10. In a telephone system, an exchange including automatic finder and connector switches for setting up connections between the lines of the system, the outlet contacts of said switches being arranged in sets each including a control contact and a pair of talking contacts, multiple conductors providing unbroken connections between the corresponding talking and control contacts of said contact sets, a trunk circuit comprising a trunk section including talking and control conductors terminating at the control and talking multiple conductors interconnecting the contacts of the contact sets having a predetermined directory number designation, a second exchange, a trunk interconnecting said trunk circuit and said second exchange, and means in said trunk circuit controllable over said trunk section for transmitting supervisory signals over said trunk.

11. In a telephone system, an exchange including automatic finder and connector switches for setting up connections between the lines of the system, the outlet contacts of said switches being arranged in sets each including a control contact and a pair of talking contacts, multiple conductors providing unbroken connections between the corresponding talking and control contacts of said contact sets, a trunk circuit comprising a trunk section including talking and control conductors terminating at the control and talking

multiple conductors interconnecting the contacts of the contact sets having a predetermined directory number designation, a second exchange, a trunk interconnecting said trunk circuit and said second exchange, and means comprising a supervisory relay controllable over the control conductor of said trunk section for transmitting supervisory signals over said trunk.

12. In a telephone system, an exchange including automatic finder and connector switches for setting up connections between the lines of the system, the outlet contacts of said switches being arranged in sets each including a control contact and a pair of talking contacts, multiple conductors providing unbroken connections between the corresponding talking and control contacts of said contact sets, a trunk circuit comprising a trunk section including talking and control conductors terminating at the control and talking multiple conductors interconnecting the contacts of the contact sets having a predetermined directory number designation, a second exchange, a trunk interconnecting said trunk circuit and said second exchange, and means comprising coacting line and lockout relays included in said trunk circuit for locking said trunk and said trunk circuit out of service when a permanent calling condition exists on said trunk.

13. In a telephone system, an exchange including a plurality of finder-connector links for setting up connections between the lines of the system, equipment common to said links and including finder start circuits, the outlet contacts of the finder and connector portions of said links being arranged in sets each including a control contact and a pair of talking contacts for subscriber line termination, multiple conductors providing unbroken connections between the corresponding talking and control contacts of said contact sets, a trunk circuit comprising a trunk section including talking and control conductors terminating at the control and talking multiple conductors interconnecting the contacts of the contact sets having a predetermined directory number designation, a trunk extending to said trunk circuit, and means comprising line and cut-off relays included in said trunk circuit and respectively controlled over said trunk and said trunk section for controlling said finder start circuits.

14. In a telephone system, an exchange including a plurality of finder-connector links for setting up connections between the lines of the system, equipment common to said links and including finder start circuits, the outlet contacts of the finder and connector portions of said links being arranged in sets each including a control contact and a pair of talking contacts for subscriber line termination, multiple conductors providing unbroken connections between the corresponding talking and control contacts of said contact sets, a trunk circuit comprising a trunk section including talking and control conductors terminating at the control and talking multiple conductors interconnecting the contacts of the contact sets having a predetermined directory number designation, a trunk extending to said trunk circuit, means comprising line and cut-off relays included in said trunk circuit and respectively controlled over said trunk and said trunk section for controlling said finder start circuits, and means comprising a lockout relay coacting with said line relay for locking said trunk circuit and said trunk out of service when a permanent calling condition exists on said trunk.

15. In a telephone system, an exchange including a plurality of finder-connector links for setting up connections between the lines of the system, equipment common to said links and including finder start circuits, the outlet contacts of the finder and connector portions of said links being arranged in sets each including a control contact and a pair of talking contacts for subscriber line termination, multiple conductors providing unbroken connections between the corresponding talking and control contacts of said contact sets, a trunk circuit comprising a trunk section including talking and control conductors

5 terminating at the control and talking multiple conductors interconnecting the contacts of the contact sets having a predetermined directory number designation, a trunk extending to said trunk circuit, means comprising line and cut-off relays included in said trunk circuit and respectively controlled over said trunk and said trunk section for controlling said finder start circuits, and means comprising a supervisory relay controllable over said trunk section for transmitting supervisory signals over said trunk.

JOHN H. VOSS.
